UNITED STATES PATENT OFFICE

161,121

TEMPERATURE-CONTROLLED VENDING CABINET

Fred A. Ossanna, Jr., Austin, Tex.

Application February 9, 1950, Serial No. 7,849

Term of patent 14 years

(Cl. D52—3)

To all whom it may concern:

Be it known that I, Fred A. Ossanna, Jr., a citizen of the United States, residing at Austin, Texas, have invented a new, original, and ornamental Design for a Temperature-Controlled Vending Cabinet, and of which the following is a specification, reference being had to the accompanying drawing, forming part thereof.

Fig. 1 is a perspective view of a temperature-controlled vending cabinet showing my new design;

Fig. 2 is a side elevational view of the cabinet;

Fig. 3 is a perspective view of the cabinet with the door in open position.

The side of the cabinet not shown is substantially the same in appearance as the side shown and the rear is plain.

I claim:

The ornamental design for a temperature-controlled vending cabinet, as shown and described.

FRED A. OSSANNA, JR.
